UNITED STATES PATENT OFFICE.

EARLY BARNETT SMITH, OF TAMPA, FLORIDA.

FLOAT-OPERATED SWITCH.

Application filed February 7, 1922. Serial No. 534,830.

The object of this invention is to improve the construction of float-operated switches.

In the accompanying drawings:—

Figure 1 shows in longitudinal section, a 5 float-operated switch constructed in accordance with the invention; Figure 2 is a cross section on the line 2—2 of Figure 1; Figure 3 is a cross section on the line 3—3 of Figure 1.

10 The drawings show a float-operated switch, embodying a casing 1 including a cup-shaped base 2 and an inverted cup-shaped body 3 having a flange 4 extended within the base, the body 3 being provided 15 with a circumscribing bead 37 engaging the upper edge of the base 2. A partition 5 extends across the body 3 and is provided with a depending marginal flange 6 attached by securing elements 7 to the body 3, as 20 shown in Figure 1. The base 2 has a lateral inlet opening 8, across which extends a screen 9. The body 3 is provided with attaching elements 10, whereby the casing 1 may be mounted on a support. The body 25 3 has a nipple 14 carrying a water-proof conduit 15, such as a piece of pipe.

An annular bracket 19, made of insulating material, is located in the casing 1 and is united by securing devices 20 with the 30 top of the body 3. Contact members 21 about against the lower surface of the bracket 19 and are held on the bracket by screws 23 or the like, the lower ends of the screws 25 entering retaining blocks 24, made of conductive material, and engaging the contact 35 members 21. At their inner ends, the contact members 21 are provided with downwardly inclined tongues 22. The annular bracket 19 has recesses 25 receiving the 40 heads of the screws 23, there being transverse passages 26 in the retaining blocks 24, binding screws 27 being threaded upwardly into the blocks 24, the binding screws entering the passages 26. Conductors 28 enter 45 the passages 26 and are bound against the screws 23 by the screws 27, an electrical connection thus being established between the conductors 28 and the contact members 21. The conductors 28 extend through the 50 conduit 15 to any desired point.

The partition 5 defines a float chamber 29

in the base 2, and in this float chamber, a float 30 is located, the float having an eccentric guide finger 31 received slidably in the partition 5, the function of the guide finger 31 being to prevent the float from rotating. The float 30 carries a stem 32 whereon a conducting bridge 33 is secured as indicated at 34, the bridge being insulated from the stem, as indicated at 35, the bridge having 60 downwardly inclined tongues 36 adapted to engage the tongues 22 of the contact members 21, as shown in Figure 1. It has been pointed out hereinbefore that the guide finger 31 prevents the float 30 from rotating and since the float cannot rotate, the bridge 33 will be located always so that when the float is in the position shown in Figure 1, the circuit, including the conductors 28, the contact members 21, and the bridge 33 will 70 be closed.

The float-operated switch above described is intended to work on a closed circuit, and it will be obvious that when the water rises to a pre-determined amount, the water, entering the opening 8, will elevate the float 30 and cause the bridge 33 to move out of engagement with the members 21, the circuit, including the conductors 28, being opened. It is obvious that, if suitable supplementary mechanisms be provided, an opening of the circuit may be caused to actuate a signal, thereby indicating that the water has risen to a dangerous extent beneath a trestle, for instance. 75 80 85 90

What is claimed is:—

An electric switch comprising contact members having their inner ends spaced apart, a bridge cooperating with the inner ends of the contact members, means for moving the bridge into and out of engagement with the inner ends of the contact members, an annular bracket and means for mounting the bracket in fixed position, the bridge operating within the annular bracket, oppositely disposed retaining blocks having openings for the reception of conductors, the outer ends of the contact members being received between the bracket and the blocks, screws passing through the bracket and the 95 outer ends of the contact members and 100 threaded into the blocks to bind the outer

ends of the contact members between the bracket and the blocks, the screws projecting into the openings of the blocks, and other screws threaded into the blocks in 5 alinement with the first-specified screws, said other screws entering the openings of the blocks and serving to bind conductors

against those portions of the first-specified screws which project into the openings.

In testimony that I claim the foregoing 10 as my own, I have hereto affixed my signature.

EARLY BARNETT SMITH.
